UNITED STATES PATENT OFFICE

CHESTER A. MACOMIC, OF CHICAGO, ILLINOIS, ASSIGNOR TO PATENT PRODUCT CORPORATION OF CHICAGO, OF WILMINGTON, DELAWARE, A CORPORATION OF DELAWARE

PATTERN BED FOR TYPECASTING MACHINES AND THE LIKE

Application filed December 15, 1928. Serial No. 326,179.

My invention relates to improvements in pattern beds such as are primarily adapted for use in line type casting machines, type setting and printing machines and the like. 5 One object of my invention is to provide in combination with a pattern bed having a plurality of longitudinally displaceable pattern pins, means for controlling the position of said pins, and means for returning them to 10 the starting position. Other objects will appear from time to time in the specification and claims.

My invention is illustrated more or less diagrammatically in the accompanying drawings, wherein—

Figure 1 is a plan view of a pattern bed;

Figure 2 is a side elevation;

Figure 3 is a section along the line 3—3 of Figure 1;

20 Figure 4 is a section along the line 4—4 of Figure 3;

Figure 5 is a perspective view showing a detail of the built up frame which carries the pattern pins.

25 Figure 6 is a section similar to Figure 3 showing the parts in a different position.

Like parts are indicated by like characters throughout.

A is a frame, preferably provided at one 30 end with pivot pin A¹. This frame is rigid and adapted to be mounted in any suitable way in a type casting machine or other apparatus. Contained within this frame are a plurality of interlocking slotted longitudinal 35 cross bars A² and transverse cross bars A³. These bars are interlocked to provide a series of pockets A⁴ in which are mounted for reciprocation one in each pocket, a pattern pin A⁵. Spring plates A⁶ are associated with 40 these cross bars, there being a pair of spring fingers in each pocket so that these spring plates hold the pattern pins yieldably in whatever position they are placed.

In Figure 2, it will be noted that the pattern bed is mounted on pins B. These pins project upwardly from a main frame B¹ and there is associated with the pattern bed and located above what may be called a plunger carriage B². This carriage has a plurality of separate plungers B³. Means not here shown

and forming no part of the present invention may be used to depress by means of any one of these plungers B³ an associated or related pattern pin. Figure 3 shows that this has been done and the pattern pin A⁵ has projected below the pattern bed so that it may engage a stop B⁴ on a moving member which is to be stopped in predetermined position by the pattern pin.

The pattern pins are arranged across the 60 bed in correlated groups, the opposed pins in groups being cut away as indicated at C. C¹ C² are a series of correcting bars extending across the bed. These bars are supported in either end in longitudinal frame members C² C² mounted for reciprocation in the direction of the axis of the pattern pins. This arrangement forms in effect a grid iron which may be moved up and down by means of a series of bell crank levers C³ having working 70 arms C⁴ engaging the frame C² and adapted to be rotated by means of a connecting rod C⁵ which extends along the machine and may be moved longitudinally to cause vertical movement of the grid iron frame and of the 75 pattern pins. It will be noted that when the bars C¹ are in the lower position as shown in Figure 3, the pattern pins are free to be forced down, their downward excursion being limited by the engagement of the head C³ with the bar C¹. When it is desired to return the pins to the starting position either for the purpose of correcting an error or to set the machine up for another operation, the parts are brought into the position shown in Figure 6, the bell crank lever is rotated in a counterclockwise direction as shown in Figure 6 and each of the bars C¹ is moved up carrying with it any of the pattern pins which may have been depressed and bringing all the pattern pins back to the upper position. When this has been done the bars are returned to the position of Figure 3 ready for the next operation. It will be noted that by this arrangement, the bar C¹ limits the movement of the pattern pin. They cannot be depressed beyond a certain point when the bars C¹ are in the down position. They cannot be raised above a certain point because they engage the underside of the bars,

thus resulting in substantial accuracy of the position of the pattern pins at all times. The movement of the bars being always in the direction parallel with the pins, there is no bending or jamming of the pins and they are free to move under the influence of the selecting or pin depressing mechanism at all times.

- The cross members A³ it will be noted 10 where they project above the pattern bed are cut away as indicated at E for the purpose of providing guide channels for the bars C¹ so that these bars are constrained to movement in a direction parallel with the movement 15 of the pattern pins and so that these bars will not be in contact with or in any way interfere with the movement of the pattern pins except in so far as they are engaged by the horizontal surfaces formed by the cut 20 away portion of the top and bottom.

Whereas in the claims I have described the transverse members as a bar it will be understood that I wish this term to be interpreted with sufficient breadth to cover any member 25 of equivalent action. In general I wish the description and drawings herein to be understood as illustrative rather than as strictly limiting me to the showing herein since many changes may be made in size, shape, number 30 and disposition of parts without departing from the spirit of my invention.

I claim:

1. In a pattern bed, a pattern pin mounted for longitudinal displacement and recessed 35 intermediate its ends, a bar extending perpendicular to the pin lying within the recess, means for moving the bar transversely to longitudinally displace the pin.

2. In a pattern bed, a pattern pin mounted 40 for longitudinal displacement and recessed intermediate its ends to provide two opposed transverse surfaces, a bar extending transversely of the pin lying within the recess, means for moving the bar transversely to bring it into contact selectively with one or other of the transverse surfaces to longitudinally displace the pin.

3. In a pattern bed, a pattern pin mounted 45 for longitudinal displacement, projecting at either end beyond the bed, recessed intermediate its ends at one side of the bed, a bar extending across the bed at one side thereof lying within the recess, means for moving the bar transversely to longitudinally displace the pin.

4. In a pattern bed, a pattern pin mounted 50 for longitudinal displacement, projecting at either end beyond the bed, recessed intermediate its ends at one side of the bed to provide two opposed transverse surfaces, a bar extending 55 across the bed at one side thereof lying within the recess, means for moving the bar transversely to cause it selectively to engage one or other of the transverse surfaces to longitudinally displace the pin.

5. In a pattern bed, a pair of pattern pins mounted for longitudinal displacement and recessed intermediate their ends in opposition one to the other, a bar lying within both said recesses, means for moving it to longitudinally displace the pins. 70

6. In a pattern bed, a pair of pattern pins mounted for longitudinal displacement and recessed in opposition to one another to provide two opposed transverse surfaces, a bar lying within said recesses, means for moving it transversely to bring it selectively into engagement with one or other of the transverse surfaces to longitudinally displace the pins. 75

7. In a pattern bed, a pair of pattern pins mounted for longitudinal displacement, projecting at one end beyond the bed, recessed in opposition to one side of the bed, a bar extending across the bed at one side thereof, lying within said recesses and means for moving it transversely to longitudinally displace the pins. 80

8. In a pattern bed, a pair of pattern pins mounted for longitudinal displacement projecting at one end beyond the bed, recessed in opposition to provide two opposed transverse surfaces at one side of the bed, a bar extending across the bed at one side thereof lying within said recesses, means for moving the bar transversely to cause it to selectively engage one or other of the transverse surfaces to longitudinally displace the pins. 85

9. In a pattern bed, a pattern pin mounted for longitudinal displacement and recessed intermediate its ends, a bar extending transversely of the pin lying within the recess, means for moving the bar transversely to longitudinally displace the pin and guide means in the pattern bed for the bar to maintain it normally out of contact with the pin. 90

10. A pattern bed comprising a plurality of interlocking cross members forming separate pockets, pattern pins slidable within said pockets and recessed intermediate their ends, a bar extending transversely of the pins located within said recesses, projections on some of said cross members in engagement with and forming guides for the bar to constrain it to movement parallel with the pins and means for moving the bar transversely to displace the pins. 105

11. In a pattern bed, a plurality of pattern pins mounted for longitudinal displacement, each pin having a transverse surface, a plurality of bars extending across the bed 110 in opposition to said transverse surfaces, a frame supporting said bars and means for moving the frame toward and from the bed to bring it into and out of engagement with said transverse surfaces. 120

12. In a pattern bed, a plurality of pattern pins recessed to provide opposed transverse surfaces, a plurality of bars lying within said recesses, a frame supporting said bars, means for moving it toward and from the bed 125 130

to bring the bars selectively into engagement with opposed transverse surfaces to move the pins toward and from the bed.

13. In a pattern bed, a plurality of pattern pins recessed to provide opposed transverse surfaces, a plurality of bars lying within said recesses, a frame supporting said bars, means for moving it toward and from the bed to bring the bars selectively into engagement with opposed transverse surfaces to move the pins toward and from the bed, the pins being arranged in opposed groups with the recesses on opposed sides of the bar so that one bar displaces all the pins of two opposed groups.

14. In a pattern bed, a pattern pin mounted for longitudinal displacement and recessed intermediate its ends, a member, generally perpendicular to the pin, penetrating the recess and means for moving the member transversely, longitudinally to displace the pin.

15. In a pattern bed, a pattern pin mounted for longitudinal displacement, and recessed intermediate its ends, a member extending across the bed and lying within the recess and means for moving the member transversely, longitudinally to displace the pin.

16. In a pattern bed, a pattern pin mounted for longitudinal displacement, and recessed intermediate its ends, a member extending across the bed and lying within the recess and means for moving the member transversely, longitudinally to displace the pin, said member being adapted to serve, when in one position, as a stop to limit longitudinal movement of the pin in one direction, and being adapted, when moved, to effect a predetermined longitudinal movement of the pin in the opposite direction.

Signed at Chicago county of Cook and State of Illinois, this 26th day of November 1928.

CHESTER A. MACOMIC.
